Raed S. Gooding

UNITED STATES PATENT OFFICE.

ISRAEL BERENSON, OF BOSTON, MASSACHUSETTS.

ELECTRIC SWITCH.

Application filed February 17, 1923. Serial No. 619,750.

To all whom it may concern:

Be it known that I, ISRAEL BERENSON, a citizen of the United States, residing at Boston, in the county of Suffolk and State of Massachusetts, have invented new and useful Improvements in Electric Switches, of which the following is a specification.

This invention relates to an electric switch and has for its object to provide a simple, compact, efficient mechanism for controlling the various audible and visible signals employed upon motor vehicles.

The invention consists in the combination and arrangement of parts set forth in the following specification and particularly pointed out in the claims thereof.

Referring to the drawings:

Figure 1 is a front elevation of an electric switch embodying my invention.

Fig. 2 is a vertical longitudinal section taken on the line 2—2 of Fig. 1.

Fig. 3 is a rear elevation of the cover plate removed from the base, together with the parts that are mounted on said cover plate.

Fig. 4 is a front elevation of the base with the cover plate removed therefrom, together with the parts that are mounted on said base.

Fig. 5 is a detail transverse section taken on the line 5—5 of Fig. 2.

Like numerals refer to like parts throughout the several views of the drawings.

In the drawings, 10 represents a circular base of insulating material, at the rear of which a hollow post 11 provided with radially arranged arms 12, 13 and 14 is secured by screws 15, 16 and 17, the heads of which constitute contact points and are located within a chamber 18 provided in the base 10, while the opposite ends of said screws are utilized as binding posts for electric wires 19, 20 and 21 which connect with electric light bulbs employed in Left, Right and Back signs respectively of a traffic signal for a motor vehicle.

A recess 22 is centrally disposed in the base 10 and communicates with the chamber 18 and rotatably mounted in said recess 22 is a cylindrical metal sleeve 23 upon the interior of which is a core 24 of insulating material, said core being held within said sleeve by inwardly bent flanges 25 and 26 provided at the front and rear ends respectively of said sleeve. A circular cover plate 27 is provided for the base 10, being fastened to the front face of said base by screws 28

and said cover plate is provided with a centrally disposed opening 29 extending therethrough through which the sleeve 23 projects. The base 10 also has a centrally disposed opening 30 extending therethrough and communicating with the recess 22. The sleeve 23 forms a part of an electric circuit and is electrically connected by a screw 31 to a wire 32, an end of which is secured in a recess 33 provided in the insulating core 24 by said screw and said wire extends rearwardly from the core 24 through the opening 30 and post 11 to a suitable location upon the frame of the motor vehicle where it is grounded in the usual well-known manner.

Secured to the core 24 in such a manner that it may rotate thereon, move longitudinally thereof and tip thereon until its rear edge contacts with the front face of the cover plate 27 is a push button 34, the main body portion of which is preferably moulded of a suitable insulating material. The push button embodies therein a sleeve 35, one end of which is embedded in the insulating material thereof and a portion of said sleeve which projects rearwardly from said material constitutes a hub upon which a contact member 36 is mounted. A disc 37 is also mounted upon the hub of the sleeve 35 with a face thereof abutting against the extremity of the contact member 36 and the latter, together with the disc 37, are both securely fastened to the sleeve 35 to form the complete push button unit by riveting the extremity of the hub of said sleeve over the outer face of said disc as illustrated in Fig. 2. The disc 37 is located within a recess 38 provided in the insulating core 24 and a spring 39, one end of which is seated within the sleeve 35 and the other end of which abuts against the bottom of the recess 38 acts to force the push button 34 outwardly and hold the disc 37 against a plate 40 which surrounds a hub portion of the contact member 36 and is always in contact therewith, thereby enabling an electric current to pass therethrough. The plate 40 is placed upon the contact member 36 during the assembling of the parts comprising the push button unit and said plate 40 is secured to the core 24 by screws 41 and 42. The screw 41 is also utilized to secure a plate 43 in the core 24, said plate 43 having a binding screw 44 mounted therein to which an electric wire 45 is attached, said wire leading to a horn provided for the motor vehicle.

A switch arm 46 is rigidly fastened to the rotatable sleeve 23 in any suitable manner, but preferably through the medium of a forked portion 47 which partially surrounds said sleeve and is soldered thereto. The switch arm 46 is constructed of resilient material and has contact fingers 48 and 49 formed integral therewith which are adapted to engage the contact screws 15 and 16 respectively when said arm is moved from a neutral position as illustrated in Fig. 1 toward the left or right. The arm 46 projects from the chamber 18 of the base outwardly through an opening 50 formed between the base and cover plate and edges 51 and 52 of said opening constitute stops to limit the movement of said arm. The arm 46 is provided with a projection 53 formed upon the rear side thereof and when said arm is located in its neutral position said arm springs rearwardly and the projection 53 enters a notch 54 formed in the base 10 and said arm is therefore securely held in its neutral position. A thumb piece 55 is provided for the outer end of the arm 46.

Another switch arm 56 is pivotally mounted at 57 to the base 10 and said arm has a contact finger 58 formed integral therewith which is adapted to engage the contact screw 17 when said arm is moved from its neutral position as illustrated in Figs. 1 and 4 toward the right. The arm 56 has a thumb piece 59 located at its outer extremity and said arm is electrically connected with the sleeve 23 through the medium of an angular member 60 which is secured between the arm 56 and the base 10 through the medium of the pivot screw 57 and a portion of said member 60 always contacts with the periphery of the sleeve 23. The arm 56 projects outwardly from the chamber 18 of the base 10 through an opening 61 formed between said base and the cover plate 27 and edges 62 and 63 of said opening 61 constitute stops to limit the movement of said arm.

The general operation of the switch mechanism which is mounted at a convenient location upon a motor vehicle as, for example, upon the steering post thereof is as follows:—If it is desired to sound the horn of the vehicle, the push button 34 is forced rearwardly until the contact member 36 engages the flange 25 of the sleeve 23 whereupon an electric circuit is completed from the wire 45 through the plate 43, screw 41, plate 40, contact member 36, sleeve 23, screw 31 and ground wire 32 and the horn is, therefore, sounded.

If it is desired to illuminate a left traffic signal indicator, the arm 46 is moved toward the left of Fig. 1 until it contacts with the stop 51, at which time the contact finger 48 engages the contact screw 15 and an electric circuit is completed, which in-

cludes the wire 19, contact screw 15, contact finger 48 of the arm 46, sleeve 23, screw 31 and ground wire 32 and the left signal is therefore illuminated.

If it is desired to illuminate a right traffic signal, the arm 46 is moved toward the right of Fig. 1 until it contacts with the stop 52, at which time the contact finger 49 will engage the contact screw 16 thereby completing an electric circuit which includes the wire 20, contact screw 16, contact finger 49 of the arm 46, sleeve 23, screw 31 and ground wire 32 and the right signal is, therefore, illuminated.

When it is desired to illuminate a back traffic signal, the arm 56 is moved toward the right of Fig. 1 until it engages the stop 63 at which time the contact finger 58 will engage the contact screw 17 and an electric circuit is thereby completed which includes the electric wire 21, contact screw 17, arm 58 of the arm 56, angular member 60, sleeve 23, screw 31 and ground wire 32 and the back indicator is thereby illuminated. When no signals are being given, the switch arms 46 and 56 are located in their neutral positions as illustrated in Fig. 1.

I claim:

1. An electric switch comprising, in combination, a base of insulating material, a cover plate for said base, a sleeve mounted to rotate in said base, said sleeve being in circuit with a source of electric supply, a core of insulating material in said sleeve, a push button yieldingly mounted upon said core and adapted to engage said sleeve to complete an electric circuit therethrough, a contact point mounted upon said base in circuit with said source of electric supply and an arm in circuit with said sleeve and adapted to engage said contact point to complete an electric circuit therethrough.

2. An electric switch comprising, in combination, a base of insulating material, a cover plate for said base, a sleeve mounted to rotate in said base and cover plate, said sleeve being in circuit with a source of electric supply, a core of insulating material in said sleeve, a push button yieldingly mounted upon said core and adapted to engage said sleeve to complete an electric circuit therethrough, a contact point mounted upon said base in circuit with said source of electric supply and an arm rigidly fastened to and in circuit with said sleeve and adapted to engage said contact point to complete an electric circuit therethrough.

3. An electric switch comprising, in combination, a base of insulating material, a cover plate for said base, a sleeve mounted to rotate in said base and cover plate, said sleeve being in circuit with a source of electric supply, a core of insulating material in said sleeve, a push button yieldingly mounted upon said core and adapted to en-

engage said sleeve to complete an electric circuit therethrough, a plurality of contact points mounted upon said base, each of said contact points being in a separate electric circuit including said source of electric supply, an arm fast to and in circuit with said sleeve and adapted to engage one of said contact points to complete an electric circuit therethrough and a second arm also in circuit with said sleeve and adapted to engage another of said contact points and thereby complete another electric circuit.

4. An electric switch comprising, in combination, a base of insulating material, a cover plate for said base, a sleeve mounted to rotate in said base and cover plate, said sleeve being in circuit with a source of electric supply, a core of insulating material in said sleeve, a push button yieldingly and rotatably mounted upon said core and adapted to engage said sleeve to complete

an electric circuit therethrough, a plurality of contact points mounted upon said base, each of said contact points being in a separate electric circuit including said source of electric supply, an arm fast to and in circuit with said sleeve, and provided with a plurality of contact fingers adapted to engage certain of said contact points to complete electric circuits therethrough and a second arm also in circuit with said sleeve and adapted to engage another of said contact points and thereby complete another electric circuit.

In testimony whereof I have hereunto set my hand in presence of two subscribing witnesses.

ISRAEL BERENSON.
